UNITED STATES PATENT OFFICE.

EDWARD G. PARRY, OF WORCESTER, MASSACHUSETTS, ASSIGNOR TO THE FOREHAND ARMS COMPANY, OF SAME PLACE.

EJECTING MECHANISM FOR BREAKDOWN GUNS.

SPECIFICATION forming part of Letters Patent No. 554,002, dated February 4, 1896.

Application filed September 7, 1895. Serial No. 561,822. (No model.)

To all whom it may concern:

Be it known that I, EDWARD G. PARRY, a citizen of the United States, residing at Worcester, in the county of Worcester and State of Massachusetts, have invented certain new and useful Improvements in Ejecting Mechanism for Breakdown Guns, of which the following is a specification.

My invention relates to shell-ejecting mechanism for breakdown guns.

The object of my invention is to provide an improved ejecting mechanism of very simple construction and operation, and my invention consists in certain novel features of construction and operation of my ejecting mechanism, as will be hereinafter fully described, and the nature thereof indicated by the claim.

Referring to the drawings, Figure 1 is a side view of a portion of a breakdown gun embodying my improvements. Fig. 2 is a side view of the inner end of the barrel detached and the barrel-lug, showing the ejector in its inward position. Fig. 3 is a central longitudinal section through the parts shown in Fig. 2. Fig. 4 is a cross-section taken on line 4-4, Fig. 3, looking in the direction of the arrow, same figure. Fig. 5 corresponds to Fig. 2, but shows the ejector in its outward position; and Fig. 6 is a central longitudinal section through the parts shown in Fig. 5.

In the accompanying drawings, 1 is the frame of a breakdown gun of ordinary construction, and 2 is the barrel portion, jointed to the front part of the frame by the pin 3 in the usual way. The barrel 2 is provided with a barrel-lug 4, which in this instance contains the ejecting mechanism. The ejecting mechanism consists of the ejector-rod 5, provided at its outer end with the ejector 6, of the ordinary construction. The rod 5 is adapted to have a longitudinal motion in a hole or recess 7 in the lower part of the barrel. A spiral spring 7 is located within the inner end of said hole 7 and is adapted to bear against the inner end of said rod 5 to force the same out, and operate the ejector to eject the shell on the breaking down of the gun.

The ejector-rod 5 has a notch or depression 5' in the lower part thereof, through which extends a pin 8, secured in the barrel-lug 4.

Said pin 8 acts to limit the outward motion of the ejector-rod, as shown in Fig. 6. The ejector-rod 5 also has a wedge-shaped notch or depression 5" in the lower part thereof, into which is adapted to extend the inner beveled end of a movable pin 9, which extends in a vertical hole 10 in the barrel-lug 4, and is adapted to have a longitudinal motion therein. A pin 12 extends in a notch 9' in said pin 9, and is secured in the barrel-lug 4, as shown in Fig. 4, and acts to limit the longitudinal motion of said pin 9, as shown in Figs. 3 and 6.

The pin 9 has a lug or projection 9" extending out from one side thereof at its outer end, as shown in Fig. 4. A flat spring 13 is secured at one end in a recess or depression in the lower side of the barrel-lug 4 by a screw 14. The free end of said spring 13 bears on the outer end of the pin 9 and acts to force said pin inwardly. The barrel-lug 4 is provided with a depression or cut-out portion 15 in one side thereof. (See Figs. 2, 4, and 5.) A screw 16 extends transversely through a threaded hole in one side of the frame 1, (see Figs. 1 and 4,) and the inner end thereof, when it is desired to operate the ejecting mechanism, extends into the depression 15 in the barrel projection or lug 4, as shown in Fig. 4, and which engages the lug 9" on the pin 9 (the end of said lug being preferably made beveled, as shown in Figs. 2 and 5) when the barrel is broken down.

The inner end of the screw 16, engaging the projection 9" on the pin 9 as the barrel is broken down, moves out said pin against the action of the spring 13, and disengages the inner end thereof from the notch 5" in the ejector-rod 5, allowing the spring 7 to act to force out said ejector-rod 5, and the ejector 6, as shown in Fig. 6, to eject the shell. After the shell has been ejected the return of the barrel to be locked to the frame moves the projection 9" away from the inner end of the screw 16, and allows the spring 13 to act to push up the pin 9 and cause the inner end thereof to engage the notch 5" in the ejector-rod 5 as said rod is forced back to its inward position by the closing of the barrel and hold said rod, as shown in Fig. 3.

In case it is desired not to have the ejecting mechanism operate, the screw 16 is turned out, so that the inner end thereof will not engage with the projection 9" on the pin 9, and said pin will remain stationary and hold the ejector-rod in its inward position when the gun is broken.

The advantages of my construction of the ejecting mechanism will be readily appreciated by those skilled in the art. It is of very simple construction and there are only a few parts, and the pin 9, which holds the ejector-rod in its inward position, is positively operated on the breaking down of the gun to release the ejector-rod and allow the same to operate to eject the shell by the screw 16 in the frame 1. The pin 9 is returned to its inward position to hold the ejector-rod by the action of the spring 13.

It will be understood that the details of construction of some of the parts of my eject-

ing mechanism may be varied somewhat, if desired.

Having thus described my invention, what I claim as new, and desire to secure by Letters Patent, is—

In the ejecting mechanism of breakdown guns, the combination with a spring-actuated ejector-rod, provided with a notch, and a movable pin which engages said notch, and a spring which holds said pin in said notch, of a screw or pin which extends transversely in one side of the frame at the front portion thereof, and engages said pin or a projection thereon upon the breaking down of the gun, to cause the same to be disengaged from the ejector-rod, and allow said rod to operate, substantially as set forth.

E. G. PARRY.
